11 Claims

ABSTRACT OF THE DISCLOSURE

In accordance with the present invention there is provided an electrical contact assembly for receiving a patchcord pin contact from both its front direction and from its side direction. The contact assembly comprises a pair of resilient spring blade members each having a relatively long longitudinal dimension and a relatively short transverse dimension. The blade members are secured in a body member remote from their front edges with the blade members being resiliently biased toward each other. Each of the blade members have a contact tip formed therein adjacent its front edge with each contact tip extending toward and opposing the other contact tip. Each contact tip has a surface flaring away from the other contact tip surface toward the front edge to form a pair of front entry flares. In addition each of the contact tip surfaces also flares away from the other contact tip surface of the blade member to form a pair of side entry flares. Thus the patchcord pin contact may be inserted from the side by way of the side entry flares to engage the tips or from the front by way of the front entry flares to engage the tips.

This is a continuation of application Ser. No. 501,832, filed Oct. 22, 1965.

This invention relates to a contact assembly and more particularly to a contact for computer patching.

In prior general purpose computers and particularly general purpose analog computers, it has been known to interconnect the differing computing elements by means of patchcords. For example, a patchbay has been provided which includes contact assemblies which are connected to the computing elements located within the computer structure. The actual patching of the patchcords is done on a removable prepatch panel and that panel is then plugged into the patchbay so that the patchcord contacts engage the patchbay contact assemblies. In this manner the computing elements are interconnected one with another as described, for example, in the text, "Electronic Analog and Hybrid Computers," by Korn and Korn, McGraw-Hill, 1964, at chapter 11.

The patchcord contacts comprise a tip or pin contact electrically connected at each of the ends of the patchcord. The patchcord tip or pin contact is inserted into and through the prepatch panel so that it extends out of the rear of that panel. The prepatch panel is thus "loaded" with patchcords away from the computer area to form a program arrangement. In this manner a computer program can be stored for later use then brought to the patchbay for immediate running of the program on the computer. To install the loaded prepatch panel in the patchbay, the prepatch panel is initially aligned so that each of the patchcord tips are to one side of and not touching its respective contact assembly in the patchbay. The prepatch panel is then moved a sufficient distance to one side to an aligned position so that each of the patchcord tips is fully engaged by its associated contact assembly. It will be understood that many thousands of patchcord tips may be engaged at one time so that a sub-

2

stantially large magnitude of force is necessary to move the prepatch panel the small amount of distance to produce engagement of the tips with the contacts. Thus, to provide this force a lever assembly or a motor drive has been required. With the prepatch panel moved from its initial position to its aligned or operative position it will be understood that patchcord tips may be plugged directly into and through the prepatch panel and they will then directly engage and forcibly bear on the contact assemblies in the patchbay. Thus the contact assemblies must be designed to be able to receive patchcord tips from their sides as well as from their front and to provide positive electrical contact.

In order to achieve these purposes many prior contact assemblies for patchbays have comprised a single spring arm formed to receive patchcord pin contacts from both their sides and their front. However such spring arm contacts have left much to be desired as they provided mechanical unbalance in the pressure applied by the single arm contact to the patchcord tip. In addition such prior assemblies did not have versatility in that they did not provide for switching operation by the use of the contacts.

Accordingly an object of the present invention is a contact assembly for a patchbay which provides for front and side entrance for a patchcord tip and balanced contact pressure on the engaged tip.

Another object of the present invention is a computer patchbay contact assembly which provides switching operations when a patchcord tip or pin contact is inserted into the contact assembly.

In accordance with the present invention there is provided an electrical contact assembly for receiving a patchcord pin contact from both its front direction and from its side direction. The contact assembly comprises contact members having first, second and third sections. The second sections being secured in a body or housing in a spaced relationship. The first sections extending outwardly from a first end of the housing and defining a pair of resilient spring blade members each having a relatively long longitudinal dimension and a relatively short transverse dimension. The blade members are secured in a body member remote from their front edges with the blade members being resiliently biased toward each other. Each of the blade members have a contact tip formed therein adjacent its front edge with each contact tip extending toward and opposing the other contact tip. Each contact tip has a surface flaring away from the other contact tip surface toward the front edge to form a pair of front entry flares. In addition each of the contact tip surfaces also flares away from the other contact tip surface in a direction generally perpendicular to the longitudinal dimension to form a pair of side entry flares. Thus the patchcord pin contact may be inserted from the side by way of the side entry flares to engage the tips or from the front by way of the front entry flares to engage the tips.

Further in accordance with the invention the body member is comprised of insulating material to electrically insulate one blade member from the other. The third sections of the contact members extend outwardly from a second end of the housing. The contact points are disposed so that they do not normally touch each other thereby to form a normally open switch. When a patchcord pin contact engages the two contact tips of the blade members a circuit is completed between the blade members through the pin contact to effectively close the switch. In addition a normally closed switch may be formed by electrically insulating the blade members one from the other and providing each blade member with a contact point which normally engage each other to electrically connect the two blade members. In addition one of the blade

members has its contact tip electrically insulated. When a patchcord pin contact is inserted to engage the contact tips, the circuit between the contact points is opened and a circuit is only completed between the patchcord pin contact and the uninsulated blade member.

The invention will be more clearly understood from following the detailed description when read in connection with the accompanying drawings in which:

FIG. 1 is a perspective view of a contact assembly embodying the invention;

FIG. 1A is a side view of a portion of a blade member shown in FIG. 1;

FIG. 2 is a perspective view of the blade member structure of FIG. 1 and a patchcord pin contact;

FIG. 3 is a perspective view of another embodiment of the invention comprising a contact assembly utilized as a normally open switch; and

FIG. 4 is a perspective view of still another embodiment of the invention comprising a contact assembly utilized as a normally closed switch.

Referring now to FIG. 1 there is shown a contact assembly 10 comprised basically of a pair of blade like spring arm members with each of the arms or blades 11a and 11b having a contact tip 12a and 12b respectively, which are formed adjacent the front edges of the blades. Both of the contact tips 12a and 12b extend toward and oppose each other. The blades 11a and 11b are formed of a single piece of resilient metal comprising an assembly 13 as best shown in FIG. 2. A positioner 11c having an enlarged end portion is formed from the same piece of metal to maintain a separation between blades 11a and 11b. A metal connection or conductor engaging tube 15 is crimped adjacent the rear edge of the blade members and is adapted to be crimped to a connecting wire thereby to make electrical connection with the contacts 11a and 11b. The rear of blade assembly 13 is disposed within a metal shell or housing with plastic insulators 16 preventing electrical contact between the blade assembly 13 and the shell 14. For purposes of explanation, the front of the blade members 11a and 11b and assembly 10 is to the left in FIG. 1 and to the right in FIG. 2 and the rear of the members and assembly is to the right in FIG. 1 and to the left in FIG. 2.

The shell 14 is adapted to be received in patchbay structure and positioned with respect to patchcord tips in a prepatch panel as described, for example, in the above text and in patent application Ser. No. 501,835 filed concurrently with this application by the same applicant and assigned to the same assignee as this application now patent No. 3,308,347 for Computer Patch Bay Formed of a Plurality of Base Blocks. Accordingly, as shown in FIG. 2 a patchcord connector 18 has a tip or pin contact 20 which is adapted to pass through an opening in the prepatch panel and is mechanically secured thereto. Thus as the patch panel is moved from its initial position to its operative or aligned position, the tip 20 moves into engagement with contact tips 12a and 12b so that these tips forcibly bear on the pin contact 20. In addition the prepatch panel may be in its operative position and the contact 18 is then plugged into a respective prepatch panel opening so that its pin contact 20 moves into direct frontal engagement with contact tips 12a and 12b.

Blades 11a and 11b may be formed of a flexible resilient material well known in the art such as annealed beryllium copper which is gold plated or phosphor bronze which has been gold plated. The blades have a substantially long longitudinal dimension, a substantially short transverse dimension and are positioned to be approximately parallel as shown in the unengaged position in FIG. 1. The blades are resiliently biased to tend to make the contact tips 12a and 12b approach each other but they are prevented from touching by the positioner 11c.

As shown in FIGS. 1, 1A and 2, the contact lips 12a and 12b are formed to have side entry flares 22a and 22b

5 to provide an entrance for pin 20 as it moves into engagement with the contact assembly 10. The surface 22a and 22b each flare away from each other toward a respective longitudinal edge 23a, 23b with the flare being rounded in shape as illustrated or flat at a 45 degree angle, for example. Thus, in operation the pin 20 pushes against the flared surfaces 22a and 22b thereby opening the contact tips 12a and 12b to allow the pin contact 20 to position itself between the tips 12a and 12b and in engagement and in electrical contact therewith.

10 There is further provided similar shaped entry flares 24a and 24b which allow the patchboard tip 20 to enter from the front of the assembly. Specifically the surface 24a and 24b each flare away from each other toward a respective blade front edge. The flares may be rounded or flat in shape so that the pin 20 pushes them apart upon engagement.

15 Front flares 24a and 24b may also be defined in the following manner. A longitudinal axis, running in the long dimension of the blades may be considered to run between and parallel to the two blades 11a and 11b. To form the front entry flares 24a and 24b the contact tips 12a and 12b respectively flare outwardly away from this longitudinal axis moving along the blades in a direction 20 toward the blade front end edges away from the body 14. As best shown in FIG. 1a, each front entry flare defines 25 a contact tip crest extending over a substantial portion of a transverse dimension of a respective blade.

20 In similar manner the side entry flares 22a and 22b 30 may be defined by considering a transverse axis which is perpendicular to the foregoing longitudinal axis. This transverse axis runs between the blades 11a and 11b and parallel to each of the blades. The side flares 22a and 22b flare outwardly from the contact tips away from the 35 transverse axis moving in a direction along the blades toward a respective one of the longitudinal edges 23a, 23b. Thus, flares 22a and 22b flare away from each other in a direction generally perpendicular to the longitudinal axis.

40 In this manner in accordance with the invention there are formed both side and front entry flares which allow the pin 20 to enter and engage the contact assembly 10 either from the side or the front. Once having made 45 engagement, the contact pressure on the tip is balanced between the two equal resilient spring arms or blades 11a and 11b.

45 In FIGS. 1 and 2 as previously described both spring contacts 11a and 11b are connected together and to the connection tube 15. Thus tube 15 is electrically connected by way of both arms or blades 11a and 11b to an engaged patchcord tip 20, FIG. 2. In FIG. 3 blades 50 30a and 30b are similar to blades 11a and 11b of FIGS. 1 and 2 except that blades 30a and 30b are electrically insulated one from the other by means of an insulated body member 31. Blade member 30a extends through the insulator body 31 to form at the rear of the assembly a connector 32a. Similarly the blade member 30b extends through insulator body 31 to form a connector 32b at the assembly rear. Connectors or conductor engaging members 32a and 55 32b of bladelike shape are engaged by suitable electrical connecting clips and are maintained separated one from the other by an additional insulator member 34. The body insulator 31 is formed of a suitable insulating material such as polypropylene and there is formed a forwardly extending insulator 35 disposed between blades 30a and 30b to maintain a separation between contact tips 37a and 37b. Thus as previously described with respect to FIG. 1, the blades 11a and 11b are biased to tend to make the contact tips approach each other but not touch. Further, the body member 31 is formed in a shape to fit 60 into a block retaining aperture of a patchbay structure.

65 In accordance with the invention the contact assembly of FIG. 3 operates as a normally open switch in its illustrated unengaged position. Accordingly, an electric circuit 70 connected between contacts 32a and 32b is in its open

circuit position. When a patchcord tip engages tips 37a and 37b, a circuit is completed between those tips so that a completed circuit may be traced by way of the connector 32a through the body member 31, arm 30a, tip 37a, a patchcord tip 20, tip 37b, arm 30b, and through the insulator 31 to the connector 32b. In this manner the contact assembly of FIG. 3 functions as a normally open switch which is closed when a patchcord tip or pin contact is inserted into the contact assembly.

Further the contact assembly of the present invention may be utilized as a normally closed switch as shown in FIG. 4. Blades 40a and 40b are similar to blades 11a and 11b of FIG. 1 and are electrically insulated one from the other. Blade member 40a extends into an insulator body member 41 and out of the rear thereof as a connector 42a. Blade member 40b extends through insulator 41 and out of the rear thereof as a connector 42b. An insulator member 44 extends from the body insulator 41 to provide electrical insulation between the connectors 42a and 42b. In addition a forward insulator 45 extends from the body insulator 41 toward the front to maintain a predetermined separation between blades 40a and 40b.

In accordance with the invention spherical contact point 46a is formed in blade 40a extending in a direction toward the other blade 40b. In a corresponding position in blade 40b a spherical contact point 46b is formed in that blade extending toward and opposing contact 46a. Each of the contact points 46a and 46b are formed in height to a magnitude slightly greater than one half the distance between blades 40a and 40b. In this manner, contact points 46a and 46b electrically contact each other with the assembly in its normal unengaged position. It will now be understood that the contact assembly of FIG. 4 provides a normally closed circuit which may be traced by way of connector 42a and through the insulator 41 to blade 40a, contact 46a, contact 46b, blade 40b through insulator 41 to connector 42b.

One of the spring arms 40a has a plastic insulating sleeve 48 molded to cover its tip 47a and extends toward the base 41 half way down the arm 40a. It will be seen that the insulating sleeve 48 may be provided by coating the blade 40a or by shrinking a plastic fitting all as well known in the art.

When a patchcord pin is inserted to engage tips 47a and 47b, the pin makes electrical contact only with the uninsulated tip 47b. In addition the patchcord pin is effective to separate the two blades 40a and 40b in a manner previously described so that the contact points 46a and 46b no longer electrically engage. Thus the normally closed electric circuit has been opened so that connector 42a no longer is connected to 42b and the patchcord tip makes electrical contact only with contact tip 47b which is electrically connected to the connector 42b. Of course when the patchcord tip is removed from engagement with the tips 47a and 47b the contact assembly of FIG. 4 returns to its normal position which is its normally closed position and connector 42a is again electrically connected to connector 42b.

Modifications of this invention not described herein will be apparent to those skilled in the art and it is intended that the matter contained in the foregoing description be interpreted as illustrative and not limiting.

We claim:

1. In an electrical contact assembly having a housing 65 of insulating material and contact members,

said contact members having first, second and third sections,

said second sections being disposed and secured in said housing in a spaced and insulated relationship, 70 said first sections extending outwardly from a first end of said housing and defining a pair of blade members having closely spaced contact tips with inwardly curved portions for engagement with a single contact member therebetween,

said third sections extending outwardly from a second end of said housing and having conductor engaging members for connection with conductor members, said conductor engaging members being insulated from each other,

means extending from said housing between said blade members to prevent said contact tips from touching, wherein the improvement comprises

each of said blade members having (1) a relatively long longitudinal dimension, a relatively short transverse dimension and (2) a front edge,

each of said blade members having one of said contact tips formed therein adjacent said front edge thereof, each contact tip having a surface flaring away from said other contact tip surface towards said front edge to form a pair of front entry flares, each said surface also flaring away from said other contact tip surface in a direction generally perpendicular to said longitudinal dimension to form a pair of side entry flares whereby said contact tips form said inwardly curved portions for engagement with said single contact member therebetween.

2. The contact assembly of claim 1 in which each of said blade members has a pair of longitudinal edges and in which each said surface also flares away from said other contact tip surface in a direction generally perpendicular to said longitudinal dimension and toward one of said longitudinal edges to form said pair of side entry flares.

3. The contact assembly of claim 1 in which each of said front entry flares defines a contact tip crest extending over a substantial portion of said transverse dimension of a respective blade member.

4. The contact assembly of claim 1 in which each of said blade members has an additional contact member, each additional contact member extending toward and opposing each other additional contact member and providing a closed electrical connection when said contact tips are unengaged with said single contact member.

5. The contact assembly of claim 1 in which said contact tips are electrically insulated from each other, each of said blade members having an additional contact member, each additional contact member extending toward and opposing said other additional contact member and providing a closed electrical connection when said contact tips are unengaged with said single contact member to provide a normally closed circuit and when said contact tips are engaged with said single contact member said electrical connection is opened.

6. The contact assembly of claim 1 in which said conductor engaging members define first and second circuit paths and said single contact member defines a third circuit path, said blade members being in a parallel relationship with said contact tips being spaced apart by an insulated extending means to permit engagement of said single contact member therebetween to electrically connect said first, second and third paths simultaneously.

7. The contact assembly of claim 1 in which said blade members are approximately parallel to each other to position said contact tips to receive said single contact member inserted parallel to a longitudinal axis running in said long dimension (1) as guided by said side entry flares for a single contact member entering from a side direction or (2) as guided by said front entry flares for a single contact member entering from a front direction.

8. In an electrical contact assembly having a housing member of insulating material and contact members, said contact members having first, second and third sections, 75 said second sections being disposed and secured in said housing in a spaced relationship, said first sections extending outwardly from a first end of said housing member and defining a pair of blade members having closely spaced contact tips with in-

wardly curved portions for engagement with a single contact member therebetween,
 said third sections being secured together and having a conductor engaging member for connection with a conductor member which extends outwardly from a second end of said housing,
 a member extending outwardly from said first end of said housing member between said blade members to prevent said contact tips from touching,
 wherein the improvement comprises
 each of said blade members having (1) a relatively long longitudinal dimension and a relatively short transverse dimension and (2) a front edge,
 each of said blade members having one of said contact tips formed therein adjacent said front edge thereof, 15
 each contact tip extending toward and opposing said other contact tip, each contact tip having a surface flaring away from said other contact tip surface towards said front edge to form a pair of front entry flares, each said surface also flaring away from said other contact tip surface towards said front edge to form a pair of front entry flares, each said surface also flaring away from said other contact tip surface in a direction generally perpendicular to said longitudinal dimension to form a pair of side entry flares whereby said contact tips form said inwardly curved portions for engagement with said single contact member therebetween.

9. The contact assembly of claim 8 in which each of said front entry flares defines a contact tip crest extending over a substantial portion of said transverse dimension of a respective blade member.

10. The contact assembly of claim 8 in which each of said blade members has a pair of longitudinal edges and in which each said surface also flares way from said other contact tip surface in a direction generally perpendicular to said longitudinal dimension and toward one of said longitudinal edges to form said pair of side entry flares.

11. The contact assembly of claim 8 in which said blade members are approximately parallel to each other to position said contact tips to receive said single contact member inserted parallel to a longitudinal axis running in said long dimension (1) as guided by said side entry flares for a single contact member entering from a side direction or (2) as guided by said front entry flares for a single contact member entering from a front direction.
